UNITED STATES PATENT OFFICE

107,881

DESIGN FOR AN ILLUMINATED CENTER- PIECE

Josephine C. Minchin, Beverly Hills, Calif.

Application July 24, 1937, Serial No. 70,603

Term of patent 7 years

To all whom it may concern:

Be it known that I, Josephine C. Minchin, a citizen of the United States of America, residing at Beverly Hills, in the county of Los Angeles and State of California, have invented a new, original, and ornamental Design for an Illuminated Centerpiece, of which the following is a specification, reference being had to the accompanying drawing, forming part thereof:

Fig. 1 is a plan view of the illuminated centerpiece showing my new design, and Fig. 2 is a front elevation of the same.

I claim:

The ornamental design for an illuminated centerpiece, as shown.

JOSEPHINE C. MINCHIN.
